EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

LINE-SPACE DEVICE FOR WRITING-MACHINES.

1,208,154.

Specification of Letters Patent.

Patented Dec. 12, 1916.

Application filed September 24, 1914. Serial No. 863,264.

To all whom it may concern:

Be it known that I, EDWARD B. HESS, a citizen of the United States of America, residing in the borough of Brooklyn, in the city of New York, county of Kings, and State of New York, have invented a new and useful Line-Space Device for Writing-Machines, of which the following is a specification.

10 This invention relates to the line spacing devices of typewriting machines and consists particularly in certain improvements of the device shown in my U. S. Patent No. 856,869 of June 11, 1907.

15 In the accompanying drawings: Figure 1 is a plan view of the left hand end of the carriage frame equipped with the line space devices of this invention; Fig. 2, an elevation of the same looking toward the left; 20 Fig. 3, a front elevation; Fig. 4 shows a casting for the space lever return spring; Fig. 5 is a plan of the back stop for the space lever, and Fig. 6, a detached sectional view of the platen shaft bearing.

25 The improvements of this invention are related to the corresponding devices shown in my U. S. patent of June 11, 1907, No. 856,869. A horizontal lever 8 is pivotally connected by a screw stud 9 to a horizontal bracket extension 10 of the carriage end frame 11. This lever and its bearing stud 9 are located forward of the carriage frame, and the link 13, connected by its forward end to the forward end of the short arm of 30 the lever 8 and by its rear end to the pawl carrying arm of the ratchet feed, acts under compression in causing the platen to rotate. The arm 14, with which the link 13 connects, has a rocking bearing coaxial with 35 the platen shaft 12 on a sleeve 15 which extends through the body of the frame 11 and through a downwardly bent extension 16 of the bracket 10 of the frame. A nut 17 fitting endwise between the body of the 40 frame and its part 16 screws on the sleeve 15 and holds it firmly in position by a shoulder on the sleeve seating against the inside of the frame. This sleeve, as will be seen by Fig. 6, affords a long bearing for 45 the platen shaft 12.

50 18 designates the ratchet wheel which connects with the platen by a clutch. 19 designates the pawl pivoted to the arm 14, 20 the pawl spring, and 21 the ratchet shield

and line space controller fitted to rock on 55 the sleeve 15.

A spring 22 is provided for moving the lever 8 back into inactive position, being connected to a short lug 23 on the lever and a screw 24 on the frame. The spring is 60 located in a tubular shield 25, shown in section at Fig. 1 and in perspective at Fig. 4. It is rigidly held by the screw 24 passing through a flattened portion at its end and by a pin 26. The rearward movement of 65 lever 8, under action of spring 22, is arrested by a stop 27 against which its short arm strikes, said stop being a projection from the stop plate 28 secured by screws to the extension 10 of the frame 11, as shown at 70 Figs. 1 and 2. A forward stop is also provided for the space lever consisting of a screw bolt having an eccentric head 29 located on the part 10 of the frame and adapted to be set to stop the lever coincidentally with the contacting of the pawl 19 with the usual stop 30. The eccentric 75 29 also provides for the varying movement of the lever 8 due to the use of ratchets of varying number of teeth.

80 The platen is set back for writing exponents or superior characters through the medium of the ratchet wheel detent locking roller and its spring 31, said spring being carried on a bracket 32 on the side of the 85 operating lever 33 mediate its pivotal end 34 and its operating knob or handle 35. The spring 31 is normally under tension with the side of the lever 33 resting against a pin 36, and the arrangement is such that 90 the lever is, by its handle, moved rearwardly when an exponent is to be written. This causes the ratchet wheel and platen to rotate backwardly, the extent of such movement to properly locate exponents being determined by the stop pin 37. When the lever 33 is released the tension of the spring 31 will ordinarily set the platen back to original line printing position and bring the lever against the stop pin 36, but to insure 100 that this return movement will always occur, a spring 38 is applied to the side of the lever 33 with a fixed point of connection to the frame 11, as at 39.

105 The detent roller is moved away from the ratchet wheel 18 to permit the platen to be freely set by a thumb wheel 43 in any position by a cam shaped roller 40 carried on

one end of a short shaft passing through the frame which has on its other end a finger piece 41, the manipulation of which turns the cam against the tail piece 42 at the end 5 of spring 31 and so, by bending the spring, moves and holds the detent roller away from the ratchet wheel.

I claim:

1. In a typewriting machine, the combination of a carriage, its front bearing, a platen mounted in the carriage, pawl and ratchet mechanism for operating the platen for line spacing, a rocker arm carrying the pawl, a horizontally arranged pawl-operating lever 15 pivoted to move about a vertical axis located forward of the front bearing of the carriage, and a link connecting the rocker arm with the pawl-operating lever.

2. In a typewriting machine, the combination of a carriage, its front bearing, a platen mounted in the carriage, pawl and ratchet mechanism for operating the platen for line spacing, a rocker arm carrying the pawl, a horizontally arranged pawl-operating lever 20 pivoted to move about a vertical axis located forward of the front bearing of the carriage, and a link connected at its rear end to the rocker arm and at its front end with the operating lever in a plane forward of the 30 front of the carriage.

3. In a typewriting machine, the combination of a carriage, its front bearing, a platen mounted in the carriage, pawl and ratchet mechanism for operating the platen for line spacing, a rocker arm carrying the pawl, a bracket extending forward from the carriage, a horizontally arranged pawl-operating lever supported by the bracket and pivoted to move about a vertical axis located 35 forward of the front bearing of the carriage, and a link connecting the rocker arm with the pawl operating lever.

4. In a typewriting machine, the combination with the carriage, the platen and the 45 pawl and ratchet for operating the platen for line spacing, of a bracket extending forward from the carriage frame, a horizontally

arranged line space operating lever pivoted to said bracket to move about a vertical axis located forward of the front bearing of the 50 carriage, a stop plate attached to said bracket and engaging the operating lever for limiting its return movement, a stop on the bracket for limiting the forward movement of the lever, a horizontally arranged 55 incased spring connected with the lever and with the bracket for turning the lever to normal position, a ratchet wheel connected with a platen, a pawl co-operating with the ratchet wheel, a rocking arm by which the 60 pawl is carried and a link connected at one end with the arm extending forward therefrom and connected at its front end with the operating lever.

5. A line spacing device for a writing machine, comprising a platen controlling ratchet wheel on a shaft having a bearing in the end frame of the carriage, a spring carried detent roller adapted to act on the ratchet wheel, a vertical lever pivoted at its 70 lower end to the carriage frame and to which the detent roller spring is secured between said pivot and the upper operating end of the lever and a forward and a backward stop between which the lever is free to move. 75

6. A line spacing device for a writing machine, comprising a platen controlling ratchet wheel on a shaft having a bearing in the end frame of the carriage, a spring carried detent roller adapted to act on the 80 ratchet wheel, a vertical lever pivoted at its lower end to the carriage frame and to which the detent roller spring is secured between said pivot and the upper operating end of the lever, a forward and a backward stop 85 between which the lever is free to move and a spring for moving and holding the lever against its forward stop.

In testimony whereof, I have hereunto subscribed my name.

EDWARD B. HESS.
